UNITED STATES PATENT OFFICE.

HAROLD B. MCGUIRE, OF FORT WAYNE, INDIANA.

SIGNAL FOR AUTOMOBILES.

1,205,098.

Specification of Letters Patent. Patented Nov. 14, 1916.

Application filed April 2, 1915. Serial No. 18,680.

To all whom it may concern:

Be it known that I, HAROLD B. MCGUIRE, a citizen of the United States of America, and resident of Fort Wayne, in the county of Allen and State of Indiana, have invented certain new and useful Improvements in Signals for Automobiles, of which the following is a specification.

This invention relates to improvements in signals for automobiles and is especially contrived to designate the intended course over which the automobile is to be driven, the signal being manipulated by the driver of the vehicle accordingly.

The object of the improvement is to provide a device that will operate effectively in daylight as well as at night, under control of the driver of the automobile, and indicate distinctly to persons approached and following, in what direction the driver intends to direct the automobile.

The object of the improvement is accomplished by the construction illustrated by the accompanying drawings in which:

Figure 1 is a front elevation of the device; Fig. 2 is a vertical section of Fig. 1 in a plane at right angles thereto, the indicating arrow being shown only partly in section; Fig. 3 is a rear view of the device showing the mechanism for actuating the indicating arrow; Fig. 4 is a diagram showing the electrical connections between the magnets that actuate the indicating arrow, the side lamps, and the controlling switches; Fig. 5 is a diagram of the indicating arrow including the automatic switch and lamps contained therein. Fig. 6 is a vertical central section through the automatic switch while in upright position; and Fig. 7 is a similar view of the same in horizontal position.

Similar numerals of reference indicate corresponding parts throughout the several views and referring now to the same 1 is a housing fixed upon the back of a supporting-plate (2), and (3) is a transparent casing fixed upon the front of the supporting-plate (2). Upon each side of the supporting-plate is mounted a reflector (4) in which is arranged a side lamp (5). These lamps and their reflectors are so disposed as to project light laterally.

Within the casing (3) is an indicating arrow (6) fixed upon a hollow shaft (7) that extends loosely through the supporting-plate (2). Upon the inner end of the hollow

shaft is a pinion (8) that meshes with a segmental gear (9), the latter being pivotally mounted upon a screw (10) that extends into a boss (11) projecting from the plate (2). The lower end of the segment (9) is flat horizontally, and a flat spring (12) bears upwardly against the flat end of the segment and the latter, due to the pressure of the spring against its flattened surface is normally held in central position. The spring (12) is held at its inner end in fixed relation with the boss (11) by means of a screw (13). To each side of the segment (9) is attached a connecting rod (14) that extends upwardly through a bracket (15) and has fixed thereon an armature (16). Over each of the armatures (16) is mounted in fixed relation with the plate (2) an electro-magnet (17) adapted, when excited, to attract the corresponding armature so that the segment will be actuated and the pinion (8) accordingly rotated. As the pinion is moved the arrow (6) is likewise turned with the shaft (7) which is fixed to the pinion. It is the intention that by exciting one or the other of the electro-magnets, the arrow will be turned from its normal vertical position to a horizontal position pointing either to the right hand or left hand accordingly as one or the other of the electro-magnets is excited. And it is a further intent that when neither of the electro-magnets is in action, the arrow will be returned to its normal vertical position, and this is accomplished by the spring (12) bearing against the flattened lower end of the segment.

The arrow (6) is made with a transparent front (18), and has mounted therein two electric lamps (19) and (20), the bulb of the former being of red glass, while the latter is of clear glass.

Within the tail of the arrow is an automatic switch composed of a block (21) of insulating material having a pocket (22) in its lower end and divergent passage-ways (23) and (24) respectively leading upwardly from the pocket. A quantity of mercury (25) is placed in the pocket (22) and rests therein while the arrow is in vertical position and makes contact with the screws (26) and (27), the inner ends of which project into said pocket. When the arrow is in horizontal position the mercury will gravitate from the pocket to the opposite end of one or the other of the passage-

ways (23) or (24) accordingly as the arrow is turned to the right-hand or left-hand. When in this position, the mercury will contact with the ends of the screws (28) and 5 (29), or (30) and (31), as the case may be. Electrical current is introduced to the lamps and switch within the arrow through the leads (32) that enter through the opening (33) that extends through the shaft. 10 One of the leads (34) is connected with each of the lamps (19) and (20). The other lead (35) has connection with the screws (27), (28) and (30). The red lamp (19) has connection with each of the screws (29) and 15 (31) and the lamp (20) has connection with the screw (26). The diagram, Fig. 4, shows each of the electro-magnets (17) with one of their terminals connected with one of the main leads (36) which is intended to be connected with one of the terminals of a source of electrical energy. The other main lead 20 (37) has connection with the other terminal of the source of energy and also with each of the push-buttons (38) and (39), and 25 each of said push-buttons has also connection with one terminal of the corresponding electro-magnet by means of connecting wires (40) and (41) respectively. The side lamps (5) have connection between one of 30 their terminals and the corresponding connecting wires (40) and (41) and their opposite terminals are connected by means of wires (42) and (43) respectively with a switch (44), and the switch has also connection 35 with the main lead (36) so that when the switch is turned "on" both lamps will have connection with said lead (36). One of the leads (34) also has connection with the switch (44) in a manner well known to 40 electricians so that when the switch is turned "on" the lead (34) will have connection with the main lead (36). The other lead (35) is connected directly to the other main lead (37). In this manner when the switch 45 (44) is turned "on" the electrical circuit through the white lamp (20) in the arrow will be completed when the arrow is in vertical position. In the operation one of the devices is placed at each end of the automobile 50 in a conspicuous place so that it may readily be observed and the push-buttons and switches are located conveniently within the reach of the driver, and the electrical connections are made accordingly as set forth. During day time the switch (44) is turned "off" so that the circuit through all 55 the lamps is broken. When the driver desires to change his course toward the right hand, he may indicate his intention by operating the push-button (39) which will close the electrical circuit through the right hand magnet (17), the effect of which causes 60 the arrow to swing and point horizontally toward the right hand. The corresponding armature (16) being attracted by the mag- 65 net has the effect of turning the segment (9) that actuates the pinion (8), causing the shaft (7) to which the arrow is fixed to turn. When it is the intention to change the course toward the left hand, the push-button (38) 70 is pressed completing the circuit through the left hand magnet (17) which causes the arrow to turn and point toward the left hand. Those persons approaching or following may ascertain the intention of the 75 driver. During night time the switch (44) is turned "on" so that one terminal of each of the lamps is connected with the main lead (36). The other terminal of the white lamp (20) in the arrow having connection 80 through the mercury (25) in the pocket with the other main lead (37) will show light. When the push-button (39) is closed the corresponding magnet and side lamp will be thrown into circuit and consequently the arrow will be turned so as to point toward the lighted side lamp, and the mercury thereupon will flow from the pocket (22) to the low end of the passage-way (24) and 85 form a connection between the screws (28) and (29), so that the red light (19) in the arrow will show while the white light (20) becomes extinguished. When the push-button (38) is closed the left hand magnet and side-lamps are thrown into circuit, and the arrow will be turned so as to point toward the lighted side lamp and the mercury will again leave the pocket and flow down the passageway (23) and connect the screws 90 (30) and (31), so that again the white lamp (20) is extinguished and the red lamp caused to glow. Thus, there appears to the observer a red arrow pointing toward a side lamp that projects its light in the direction the driver intends to steer. When the intention is to drive straight ahead the arrow is left in vertical or normal position, and at 95 night shows constantly a white light, signifying "straight ahead." By arranging the side lamps and their reflectors angularly outward from the sides of the case, as appears in Fig. 1, the lights as projected from them, being at an angle toward the intended direction of travel is inherently significant 100 of its meaning. 105

What I claim is:—

In apparatus of the class described, a supporting plate, a housing fixed upon the back thereof, a transparent casing fixed upon the front of the plate; an oscillating hollow shaft mounted centrally in the plate and having a pinion fixed upon its rear end; a hollow arrow having a translucent front face and being mounted fixedly upon the shaft within the casing; a pivoted segment within the housing engaging the pinion and having a flat face; a flat spring bearing against the face and adapted to hold the segment normally in central position; two connecting rods in connection with the seg- 110 115 120 125 130

ment, one upon each side of its pivotal point, and each having an armature fixed upon its upper end; a corresponding pair of electro-magnets positioned respectively above the 5 armatures; a series of electric lamps mounted within the arrow and distinguished from each other in color; conductors extending through the shaft for conveying current to the lamps within the arrow; a switch within 10 the arrow in connection with the conductors

and lamps for completing the various circuits leading to the several lamps accordingly as the arrow is turned; and means for selectively exciting the electro-magnets.

In testimony whereof I affix my signature, 15 in presence of two witnesses.

HAROLD B. McGUIRE.
